UNITED STATES PATENT OFFICE

ROY H. ZINKIL, OF OAK PARK, ILLINOIS, ASSIGNOR TO CRANE CO., OF CHICAGO, ILLINOIS, A CORPORATION OF ILLINOIS

DESIGN FOR A DRINKING FOUNTAIN BUBBLER HEAD

Application filed October 23, 1931. Serial No. 41,496. Term of patent 14 years.

To all whom it may concern:

Be it known that I, Roy H. Zinkil, citizen of the United States, residing at Oak Park, in the county of Cook and State of Illinois, whose post-office address is 406 North Cuyler Avenue, Oak Park, Illinois, have invented a new, original, and ornamental Design for a Drinking Fountain Bubbler Head, of which the following is a specification, reference being had to the accompanying drawings, forming part thereof.

In the drawings:

Fig. 1 is the top view of the article showing my new design.

Fig. 2 is a side view.

Fig. 3 is an end view.

I claim:

The ornamental design of a drinking fountain bubbler head substantially as shown.

ROY H. ZINKIL.
